(57) **CLAIM**

The ornamental design of a transition fairing, as shown and
described.

DESCRIPTION

FIG. 1 is a perspective view of a transition fairing according
to our new design;

FIG. 2 is front view of the transition fairing of FIG. 1;
FIG. 3 is a left side elevational view of the transition fairing of
FIG. 1;

FIG. 4 is a top view of the transition fairing of FIG. 1; and,
FIG. 5 is a bottom view of the transition fairing of FIG. 1.
FIGS. 1-5 illustrate a first embodiment of our novel design
suitable for use on the left side of a vehicle. Our novel design
also includes a second embodiment suitable for use on the
right side of a vehicle, which is mirror symmetrical to FIGS.
1-5 and therefore not separately illustrated.
